UNITED STATES PATENT OFFICE

CHARLES H. HALL, OF FREEPORT, NEW YORK

DESIGN FOR A MOLDED CONTAINER CLOSURE

Application filed April 26, 1932. Serial No. 43,615. Term of patent 14 years.

To all whom it may concern:

Be it known that I, CHARLES H. HALL, a citizen of the United States of America, residing at Freeport, L. I., in the county of Nassau and State of New York, have invented a new, original, and ornamental Design for Molded Container Closures, of which the following is a specification, reference being had to the accompanying drawing, forming part thereof.

Fig. 1 is a plan view of a molded container closure showing my new design.

Fig. 2 is a partial section through the molded container closure of Fig. 1.

Fig. 3 is a perspective view of the molded container closure shown in Fig. 1.

The dominant characteristics of the closure are the substantially flat skull and bones lying in a horizontal plane and forming a compact unitary design with the cap.

I claim:

The ornamental design for a molded container closure, as shown and described.

In testimony whereof, I affix my signature.

CHARLES H. HALL.
